(57) **CLAIM**

We claim the ornamental design for a firearm sling, as shown and described.

DESCRIPTION

FIG. 1 is a top right rear isometric view of the firearm sling, showing our new design.

FIG. 2 is a bottom right rear isometric view thereof.

FIG. 3 is an enlarged front view thereof.

FIG. 4 is an enlarged rear view thereof.

FIG. 5 is a left view thereof.

FIG. 6 is a right view thereof.

FIG. 7 is a top view thereof; and,

FIG. 8 is a bottom view thereof.

The broken lines shown in the drawings illustrate structure or features of the firearm sling that form no part of the claimed design.

The straight-line surface shading and stippling shown in the drawings to represent the surface contours of the design, and are not intended to indicate surface decoration.
